[57] CLAIM

The ornamental design for a pneumatic sensor, as shown and described.

DESCRIPTION

FIG. 1 is a perspective view of our novel pneumatic sensor

showing in phantom a mounting bracket therefor;

FIG. 2 is a top plan view thereof;

FIG. 3 is a side elevational view thereof;

FIG. 4 is a bottom plan view thereof;

FIG. 5 is a front elevational view thereof;

FIG. 6 is a rear elevational view thereof;

FIG. 7 is a side elevational view of a first alternate embodiment of our novel pneumatic sensor, the opposite side elevational view being a mirror image thereof;

FIG. 8 is a rear elevational view of the pneumatic sensor shown in FIG. 7, the top and bottom views of the embodiment shown in FIG. 7 being identical to those shown in FIGS. 2 and 4;

FIG. 9 is a perspective view of a second alternate embodiment of our pneumatic sensor;

FIG. 10 is a top view of the pneumatic sensor shown in FIG. 9;

FIG. 11 is a side elevational view of the pneumatic sensors shown in FIG. 9;

FIG. 12 is a bottom plan view of the pneumatic sensor shown in FIG. 9;

FIG. 13 is a front elevational view of the pneumatic sensor shown in FIG. 9; and,

FIG. 14 is a rear elevational view of the pneumatic sensor shown in FIG. 9.

The broken line showings are for illustrative purposes only and form no part of the claimed design.
